RATCHET WRENCH

Allen Walton, Cheney, Wash.

Application January 20, 1933, Serial No. 652,633

3 Claims. (Cl. 81—60)

My invention relates to an improvement in ratchet wrenches, and the objects of my improvement are: First, to include all of the useful features of ratchet wrenches now in use; and second, to add a means of rapidly screwing or unscrewing a nut or bolt as soon as it is sufficiently loosened to turn easily, thus speeding up materially the work of applying or removing bolted parts.

- 10 I attain these objects by the device illustrated in the accompanying drawing, in which: Figure 1 is a plan view of the entire wrench and Figure 2 is a side elevation with the frame and one gear shown in section.
- 15 The socket holder 1, controlled by the ratchet dog 2, may be rotated either by turning the main handle 3 in the ordinary way or through the action of handle 4 acting through the gear train 5, 6, 7, 8. Pinion 5 is associated with gear 6 through the ratchet 9. Meshing of these two ratchet wheels is insured by spring 10. Springs also control the ratchet dog 2 and handle 4. When used to remove a nut, the socket is fitted to the nut and the wrench turned by handle 3 as in the ordinary ratchet wrench. As soon as the nut has been loosened, handles 3 and 4 are squeezed together and the nut is spun off with one or more strokes of handle 4. During this action, socket holder 1 is prevented from reversing direction by dog 2, and handle 4 is permitted by the ratchet 9 to restore itself under the action of a suitable spring to normal position after being squeezed. If the nut is to be screwed on instead of removed, the socket is applied with the wrench turned over; the nut is spun down and tightened by a reversal of the above process. It will be understood that ratchet dog 2 could be applied to wheel 8 as well as to socket holder 1, or that ratchet 9 could be applied to wheels 7 and 8 instead of wheels 5 and 6 without changing the principle upon which the device operates. It will also be understood that I do not limit myself to any particular gear ratio in proportioning the

gears used, nor to any definite number of gears, since in some applications a high gear ratio may be desirable, while in others a lower gear ratio may be better. The device may, of course, be built in a variety of sizes.

I claim:

1. In a ratchet wrench, a frame including a handle and a head portion, a socket holder rotatably mounted in said head portion, said socket holder having secured thereto a first gear and a ratchet member, a dog carried by said frame and engageable with said ratchet member, a gear train carried by said frame one gear of which meshes with said first gear and another gear of said train having a ratchet portion, and a second handle pivoted to said frame and having a gear segment at one end meshing with a gear having a second ratchet member in ratchet engagement with the ratchet portion of said gear train.
2. In a ratchet wrench, a combination of a socket holder, a ratchet and a gear forming one unit rotatively mounted in the frame of said wrench, a dog engaging said ratchet and supported by said frame, a gear train engaging said gear and socket holder unit and mounted on said frame, a gear of said train having a ratchet portion, a handle pivoted to said frame and carrying a gear segment meshing with a gear and ratchet unit in ratchet engagement with the ratchet portion of said gear train.
3. In a ratchet wrench, a combination of a socket holder, a ratchet and a gear forming one unit rotatively mounted in the frame of said wrench, which frame is also the handle, a dog engaging said ratchet and supported by said frame, a gear train engaging said gear and socket holder unit and mounted on said frame, a gear of said train having a ratchet portion, a secondary handle pivoted to said frame and carrying a gear segment meshing with a gear and ratchet unit in ratchet engagement with the ratchet portion of said gear train.

ALLEN WALTON.
